COMBINATION PENCIL AND MEMORANDUM
PAD HOLDER

Adren Anthony Kingmon, Cincinnati, Ohio

Application August 18, 1947, Serial No. 140,938

Term of patent 14 years

(Cl. D74—1)

To all whom it may concern:

Be it known that I, Adren Anthony Kingmon, a citizen of the United States, residing at Cincinnati, in the county of Hamilton and State of Ohio, have invented a new, original, and ornamental Design for a combination Pencil and Memorandum Pad Holder, of which the following is a specification, reference being had to the accompanying drawing, forming part thereof.

Fig. 1 is a front perspective view of a combination memorandum pad holder showing my new design.

Fig. 2 is a fragmentary perspective view of the upper left hand portion of Fig. 1 with the pencil withdrawn.

Fig. 3 is a side elevational view thereof.

I claim:

The ornamental design for a combination pencil and memorandum pad holder, as shown.

ADREN ANTHONY KINGMON.
